UNITED STATES PATENT OFFICE

155,293

DESIGN FOR A FINGER RING

Frederick J. Kuczajda, Windsor, Ontario, Canada,
assignor to Motif Manufacturing Co., Inc., De-
troit, Mich.

Application June 9, 1948, Serial No. 146,865

Term of patent 7 years

(Cl. D45—10)

To all whom it may concern:

Be it known that I, Frederick J. Kuczajda, a citizen of the United States, residing at Windsor, Province of Ontario, Canada, have invented a new, original, and ornamental Design for a Finger Ring, for which the following is a specification, reference being had to the accompanying drawing, forming a part thereof, in which:

Figure 1 is a side elevational view of the finger ring showing my design; and

Figure 2 is a plan view thereof, on a larger scale.

The side of the finger ring not shown in Figure 1 is identical with the side thereof which is shown.

I claim:

The ornamental design for a finger ring, substantially as shown and described.

FREDERICK J. KUCZAJDA.
